STEAM TRAP.

No. 594,795.

Patented Nov. 30, 1897.

UNITED STATES PATENT OFFICE.

BURTON W. HILL, OF SOMERVILLE, MASSACHUSETTS.

STEAM-TRAP.

SPECIFICATION forming part of Letters Patent No. 594,795, dated November 30, 1897.

Application filed February 1, 1897. Serial No. 621,393. (No model.)

To all whom it may concern:

Be it known that I, BURTON W. HILL, of Somerville, in the county of Middlesex and State of Massachusetts, have invented certain new and useful Improvements in Steam-Traps, of which the following is a specification.

This invention relates to steam-traps of the class known as "gravity-traps," which have a movable chamber or receiver for the water of condensation, the chamber receiving water when in a raised position and receiving steam to expel the water when in a depressed position.

15 The object of the invention is to provide an automatic vent for traps of this description which shall be automatically opened to release the air and steam entrapped in the chamber when the latter is in position to receive 20 water and automatically closed when the chamber is in position to receive steam for the purpose of discharging the water.

The invention consists in the improvements which I will now proceed to describe and 25 claim.

30 Of the accompanying drawings, forming part of this specification, Figure 1 is a side view of one form of steam-trap embodying my invention, in which one side of the receiving-chamber is shown partially broken away. Fig. 2 is a partial side view of the same in a different position. Fig. 3 is a side view of my improved valve and vent. Fig. 4 is a section on line 4 4 of Fig. 3. Fig. 5 is a section 35 on line 5 5 of Fig. 4. Fig. 6 is a section on line 6 6 of Fig. 1. Figs. 7, 8, and 9 are views showing a modified form of my invention.

Similar letters of reference indicate corresponding parts in all the figures.

40 The drawings show a type of steam-traps similar to that illustrated in my Patent No. 550,886, dated December 3, 1895, the said trap being adapted to receive the water of condensation from a steam-heating system and to 45 return said water to the boiler or source of steam-supply; but my present invention, as hereinafter disclosed, is not restricted in its application to this particular form of steam-trap.

50 In the drawings, *a* represents a chamber of suitable form adapted to receive the water of condensation through a fixed hollow shaft *s*, on which said chamber is adapted to oscillate. A counterbalancing-weight *b* is connected

55 with the chamber and a rolling weight *c* co-operates with the chamber and with the weight *b*, as described in the above-mentioned patent. The chamber is elevated, as shown in Fig. 1, when receiving water of condensation, and remains elevated until sufficient water has 60 accumulated in it to overbalance the weight *b*. The chamber then swings downwardly to the position shown in Fig. 2, its downward movement being limited by a stop *a'*. This action opens a valve, as described in said patent, and allows live steam from the boiler to 65 pass through pipes *d* and *e* into the chamber *a*. The steam forces the water from said chamber through the hollow shaft and through suitable pipes back to the boiler or 70 to a receiving vessel. The apparatus then assumes its former position and the water of condensation from the system again accumulates in the chamber *a*.

The rolling weight *c* is movable on a track 75 *c'*, which moves with the chamber, the object of said weight being to hold the chamber in either of its extremes of position, the weight *c* holding the chamber in the position shown in Fig. 1 until it has been filled, when it is 80 caused by the tipping of the chamber to the position shown in Fig. 2 to hold the chamber in the last-mentioned position until it is emptied, the chamber being then returned to the position shown in Fig. 1 by the weight *b*. 85 When the chamber *a* begins to fill again with water, it is desirable to have a vent for the air or steam which may be entrapped in the chamber and hinder the ingress of the water. It is the object of my present invention to 90 provide an automatic vent for this purpose which shall be open when the chamber is in its raised position and the water is entering and closed when the chamber is depressed and steam is admitted to expel the water. 95

My improvement is embodied in the construction next described.

f represents a valve-casing which is attached to the upper portion of the chamber *a* and communicates with the interior thereof. 100 In the casing *f* is a valve-seat *f'*, from which extends a vent-passage *f''*.

f'' is a valve formed to close on the seat *f'* and having a stem *f''*, which is movable in the vent-passage *f''*. A portion of the valve-stem, 105 as here illustrated, is of triangular cross-section, which allows the air or steam from the chamber *a* to pass upwardly through the vent-

passage f^3 when the valve is open. A head f^4 is secured by a screw f^6 to the upper end of the valve-stem, said head being pivoted at f^8 to an elongated guide g , which supports a 5 rolling weight g' . The said guide is pivoted at g^5 to a standard or lug f^5 , affixed to the casing f , and constitutes a lever which is tilted on its pivot or fulcrum g^5 by the weight g' . The said weight has a peripheral groove g^6 to 10 receive the inner edges of the two bars of the guide, as shown in Fig. 6. When the chamber a is depressed, as shown in Fig. 2, the guide g is so inclined as to cause the weight g' to roll to the left-hand end of the guide, as 15 viewed in said figure, the weight depressing that arm of the guide and raising the other arm, which is connected with the valve-stem. The valve f^2 is thus raised and closed against its seat, preventing the escape from the chamber 20 of any of the steam which is now being introduced to expel the water. When the water has been expelled and the chamber returns to the position shown in Fig. 1, the guide g is inclined in the opposite direction 25 and the weight g' rolls to the right-hand end of the guide, depressing the arm which is connected with the valve and separating the valve from its seat, as shown in Fig. 4, thus opening the vent-passage f^3 and permitting 30 the entrapped air or steam to escape before the water which is now entering the chamber.

The operation is thus continued, the vent-passage being closed when the chamber assumes its steam-receiving position and opened 35 when the chamber assumes its water-receiving position.

The guide g is preferably fulcrumed so that its arms differ in length, the arm to which the valve is connected being longer than the other. 40 This arrangement gives the weight sufficient force to open the valve against the pressure in the chamber a .

The construction illustrated in Figs. 7, 8, and 9 is a modified form of my invention in 45 which a muffler t is applied to the vent-opening f^3 to deaden the sound of escaping steam and air and also to prevent the same from issuing directly into the atmosphere. In this modified construction it is desirable to place 50 the automatic vent in a position nearer the axis of rotation of the trap than that which it occupies in Figs. 1 and 2. Figs. 7 and 8 show, respectively, side and end elevations of the trap with the automatic vent and the muffler attachment. h represents the casing of the 55 valve controlling the entrance of live steam to the chamber a . The automatic vent is preferably mounted on this casing, but may be situated at any convenient point between the said valve and the upper termination of the steam-pipe e . t' represents a conducting-pipe leading from the exhaust-opening or 60 vent-passage f^3 , Figs. 3 and 4, to the muffler t , the purpose of this pipe being to conduct 65 the imprisoned steam and air which passes from the chamber a and through the pipe e and the automatic vent to the said muffler t .

The muffler t is mounted on a suitable fixed support in line with the trap's axis of rotation and is provided internally with a diaphragm or series of diaphragms t^2 , having perforations or ports so arranged that the steam or air which enters the muffler through the pipe t' is compelled to pursue a devious path in traversing the diaphragms. Any noise or hissing is thereby prevented and the steam, air, or water is allowed to escape from the muffler through a pipe t^3 to the sewer or to a receptacle or merely to the outside air. The conducting-pipe t' enters the muffler through 75 a sleeve t^4 formed thereon, and is adapted to rotate in said sleeve when the trap turns on its axis. A suitable packing is provided in the sleeve t^4 , whereby the joint is rendered steam-tight. 80

I do not confine myself to the use of the particular form of muffler herein illustrated and described, nor to the use of any muffler whatever in connection with the automatic vent, as shown in Figs. 7 and 8. I may use 90 simply a flexible tube leading from the vent to the sewer or any convenient receptacle. 85

I claim—

1. In a steam-trap, a movable chamber having a vent, a valve having a stem movable in 95 said vent, a lever fulcrumed at one side of the stem and having one of its arms connected with the stem, said lever being formed as a guide, and a weight movable on said lever and adapted to tilt the same to open and close 100 the valve.

2. A steam-trap comprising in its construction an oscillatory chamber having a counter-balancing-weight and a track and rolling weight for holding the chamber in either of 105 its extremes of position, said chamber having a vent in its upper portion, a valve having a stem movable in said vent, a lever fulcrumed at one side of the stem and having one of its arms connected with the stem, said 110 lever being formed as a guide, and a weight movable on said lever or guide and adapted to tilt the same to open and close the valve.

3. An automatic vent attachment for steam-traps, the same comprising a casing adapted 115 for attachment to the water and steam receiving chamber of the trap, and having a vent-passage, a valve in said casing adapted to close said passage, and having a stem projecting from the casing, a lever fulcrumed to 120 a support on the casing and having one arm connected with the valve-stem, said lever being formed as a guide, and a rolling weight movable on said lever and adapted to tilt the 125 same, when the chamber is moved from one position to the other.

In testimony whereof I have signed my name to this specification, in the presence of two subscribing witnesses, this 25th day of January, A. D. 1897.

BURTON W. HILL.
